UNITED STATES PATENT OFFICE.

CHARLES GÉGAUFF, OF MULHOUSE, FRANCE, ASSIGNOR TO SOCIÉTÉ ALSACIENNE DE CONSTRUCTIONS MÉCANIQUES, OF MULHOUSE, FRANCE.

MEANS FOR ACTUATING THE CUSHION PLATE IN HEILMANN AND LIKE COMBERS.

Application filed September 30, 1926, Serial No. 138,754, and in France November 23, 1925.

The present invention relates to combers of the Heilmann type having rocking nippers and detaching means consisting of rollers. In these combers the cushion plate has for its object to ensure that during the detaching operation the lap will remain in engagement with the needles of the fixed comb because the fibres tend always to escape from the combing action of the needles of the fixed comb and to pass beneath the needles rather than through them.

The object of the present invention is to effect improvements in the means for carrying and operating the cushion plate or pressing in device, and which secures very smooth movement of the cushion plate dependent solely upon the movement of the lower npper jaw.

With the above and other objects in view, the invention consists in the construction, combination and arrangement of devices hereinafter described and claimed.

In the accompanying drawings,

Figure 1 is a diagrammatic sectional view of so much of a combing mechanism of the Heilmann type as includes my present improvements in a preferred form.

Figure 2 is a similar view of a modified construction of the same.

Figure 3 is a similar view of another modified construction of the same.

Figure 4 is a similar view of another modified construction of the same.

The cushion plate *a* (see Fig. 1) at the moment of commencement of the detaching operation should be placed beneath the lap so as to support it and remain very close behind the needles *b* of the fixed comb but while the detaching operation is being carried out the fixed comb *b* advances slightly towards the detaching roller *c* as also the lap itself while the nippers *s* remain generally stationary. It is thus necessary that the cushion plate *a* should then follow the slight advancing movement of the fixed comb *b* so that it always remains close behind the needles. This slight advancing movement is effected by a cam *e* located on the continuously rotating shaft *f* of the comber. According to the cottons being treated, it is necessary to modify the amplitude and the form of this slight advancing movement which is obtained by displacing the pivot *g* in its guide to modify the amplitude and by changing the form of the cam *e*,

that is to say, replacing it by another to modify the form of this movement.

On the other hand when detachment of the lap by the roller *c* is completed the unit formed by the nippers *d*, *d*₂, the fixed comb *b* and its arm *h*, the grid *i* and the arm *u* of the carriage carrying this unit has imparted to it a translatory movement by means of a lever rocking about the fixed pivot *m* mounted on the framework of the comber, the lever *l* pivoting at *k* about the end of the arm *u* in such manner that the nose *d* of the nippers (then closed) is brought into the position *d*₁ which it occupies during combing of the lap by the circular comb *n* (see Fig. 1). The arm *l* will then occupy the position *l*₁ shown in dotted lines and the cushion plate *a* will then occupy the position *a*₁ indicated in dotted lines, and the guide lever *o* will occupy the position *o*₁ indicated in dotted lines, the axis *p* about which the support for the cushion plate *a* pivots will be moved to *p*₁, the other arm *q* of the lever *p*, *t*, *q*, will be moved to *q*₁ and the lever *r* will occupy the position *r*₁ the pivoting axis *v* of the lever remaining fixed.

The cushion plate during the movement towards the circular comb *n* of the whole of the nippers must then move relative to the nippers *d* in such manner that when it reaches the combing position (shown in dotted lines) the nose of the cushion plate *a* will be withdrawn beneath the nippers and occupy a position *a*₁ outside of the path of the needles of the circular comb *n* so as not to interfere with the combing of the lap and so as to avoid contact with the needles which would damage them.

When the combing of the lap is completed i. e. after passage of the needles of the comb *n* the nippers are displaced again in the opposite direction, i. e. towards the detaching rollers *c*, *c*₁ for the detaching operation. During this displacement the cushion plate *a* will again slide beneath the nippers *d* and be moved in relation to the nippers which will bring it again into the position it should occupy at the commencement of the detaching operation viz.—the position represented in Figs. 1, 2, 3 and 4. The detaching operation again commences as described above and the operations are repeated in this order. The plate *a* should thus receive relative movements with respect

to two distinct devices but if the plate a does not at the end of the detaching operation and before the commencement of the movement of the whole towards the combing position, occupy always the same position in relation to the nippers d (following a modification of the form of the movement of the fixed comb b due to change in the cotton being combed) its final position a will not always be the same and serious disadvantages will result, the plate a not being withdrawn sufficiently beyond the reach of the teeth of the comb n .

The actuating means forming the subject of the present invention has for its object to cause the cushion plate always to occupy the same position during combing whatever be the form of movement of this plate, during the detaching operation to follow the fixed comb. This means is essentially characterized in that the members imparting to the cushion plate a in the first place a movement following the movement of the fixed comb and in the second place a movement relatively to the nippers are rigidly connected together in such manner that the cushion plate retains always in relation to each of those two members the same relative positions.

In Fig. 1 the cushion plate a is carried by a small knee lever s pivoting about a pivot t carried by an arm u on the carriage carrying the whole of the nippers d , d_2 and other parts such as the fixed b and grid i .

The end q of the pedal lever s is pivoted to a rod r itself pivoting about the pivot v . The position of this point v is so selected that if the latter remained fixed in space during the displacement of the whole of the nippers that is to say, from the detaching position to the combing position, the plate a would be moved relatively to the nippers d , that is to say, would be displaced from the position a to that a_1 shown in dotted lines in Fig. 1. Thus these alternate movements of the whole of the nippers from d to d_1 would produce the relative alternate movement of the plate from a to a_1 .

To obtain the other movement of the plate i. e., the movement of displacement to conform to that of the fixed comb b during the detaching operation the point v to which the lever r is pivoted is located at the end of a lever pivoting about the fixed pivot w and pivoting at z_1 on the rod z effecting the movement of the comb b of a form determined by the profile of the cam c carried by the shaft f and acting on z through the medium of the lever x pivoted at a fixed point x_1 .

It will thus be seen that if at the conclusion of the detaching operation the plate a occupied a position different from that which it should occupy so as to come always into the position a_1 i. e., so as to oc-

cupy always the same position during the detaching operation, the point v about which the lever r pivots during the translatory movement from detaching position to combing position is also displaced by an amount 70 corresponding to that of the displacement of the cushion plate a during the detaching operation and consequently the relative movement of the point q in relation to the arm u remains always the same, and the same 75 may be said of the definite position of the plate a .

Fig. 2 shows a variant of the actuating means shown in Fig. 1. The only difference compared with Fig. 1 consists in the arrangement of the levers x pivoting about x_1 and w_1 and transmitting the movement of the cam c on the one hand directly at z_2 , to the actuating rods of the fixed comb b and on the other hand through the medium of 85 the rod z pivoting at z_1 on the lever y to the point v at which is pivoted the rod r effecting as in Fig. 1 the displacement of the plate a . The operation is the same as in Fig. 1.

Fig. 3 shows a third embodiment of the new mechanism in which the rod r controlling the movement of the plate a is a lever pivoting on the one hand about the axis u_1 , carried by the arm u and on the other hand at r_2 on the support for the plate a . The lever r terminates in a roller r_1 adapted to roll over the tail v_1 of the lever y to which is imparted at z_1 the movement of the cam c .

In this manner the action of the cam v_1 of the lever y on the roller r carrying the plate pivoted at r_2 causes the advance during the detaching operation of the plate in accordance with the movement of the fixed comb b and the operation is analogous to that of the construction shown in Fig. 1 because the roller r remains stationary during the movement of the carriage u from the detaching position of the combing position, and the lever r turns about the pivot 105 of this roller.

Fig. 4 shows a variant analogous to that shown in Fig. 3. In this construction the cam v_1 and the roller r of Fig. 3, are replaced by a link v_2 pivoted at the one end 115 at v the end of the lever y and on the other end r_3 on the end of the lever r to which is pivoted at r_2 the support of the cushion plate. The operation is analogous to that of the arrangement shown in Fig. 3.

In all this embodiments it has been assumed that the movement of displacement of the fixed comb is effected by means of the cam just as the displacement from the detaching position to the combing position of the nippers has been assumed to be effected by means of a lever pivoted on a fixed pivot of the frame work of the comber, but it is obvious that the invention is applicable whatever be the arrangement employed for 125 130

effecting these two movements of advance of the cushion plate and of translation of the nippers carrying carriage the mechanical means ensuring their connection may 5 vary as also the devices themselves.

What I claim is:

1. In combing mechanism of the Heilmann type, in combination with a lower nipper jaw and means to actuate the same, a 10 lever permanently pivotally connected to and carried by said jaw, a cushion plate ar-

ranged below said nipper jaw and pivotally connected to said lever, and means to actuate said lever and hence also said cushion plate.

2. Combing mechanism as claimed in claim 1, in which the cushion plate lever actuating means is independent of the means for actuating the lower jaw.

In witness whereof I affix my signature.

CHARLES GÉGAUFF.
